UNITED STATES PATENT OFFICE

EARL A. BESSOM, OF MARBLEHEAD, MASSACHUSETTS, ASSIGNOR TO UNITED SHOE MACHINERY CORPORATION, OF PATERSON, NEW JERSEY, A CORPORATION OF NEW JERSEY

HEEL-SEAT FORMING MACHINE FOR OFF-THE-LAST WORK

Application filed April 27, 1929. Serial No. 358,655.

This invention relates to machines for use in the manufacture of shoes and is herein illustrated as embodied in a machine for forming the heel-seats of shoes.

In the use of heel-seat forming machines of the type disclosed in United States Letters Patent No. 1,674,085, granted June 19, 1928, upon application of Milton H. Ballard et al., and in United States Letters Patent No. 1,706,278, granted March 19, 1929, upon application of René E. Duplessis, it has been the practice to mold the heel-seat portions of shoes, thereby to shape them for receiving the concaved attaching faces of wood heels, while the shoes are mounted upon lasts. In machines of the type above mentioned the last is supported upon a block carried by a jack which is movable into and out of position under the die to position the shoe in operative relation to the die and to place it in a position to facilitate the removal of a shoe from the jack and the placing of another shoe thereon and which is movable toward and away from the die to effect the forming operation, the block being provided with a last pin to enter the thimble of the last.

In the manufacture of some types of shoes, for example McKay shoes, after a shoe has been lasted and an outsole laid thereon the last is removed in order to permit attachment of the sole by through-and-through stitching through the upper and insole, and the shoe is then leveled by direct pressure while the shoe is supported by a heavy iron form which accurately fits the inside sole portion of the shoe. At this stage in the manufacture of the shoe, in order to facilitate holding of the shoe during the edge trimming and edge setting operations which are next performed, the shoe is removed from the iron form and a second last has to be placed in the shoe but the second last used in these operations is not usually of a character to enable the heel-seat forming operation to be carried out, since, for the edge trimming and edge setting operations, it is not necessary that the last fit the shoe accurately. Hence this last is removed before the heel-seat forming operation.

In order that the heel-seat forming oper-

ation may be performed satisfactorily while the shoe is off the last, it is necessary that the rear part of the sole portion of the shoe be rigidly supported inside the shoe to oppose the action of the heel-seat forming die, and that the shoe be held from lateral and longitudinal movement with respect to such internal support.

Objects of this invention are to provide a machine of the type disclosed in the above-mentioned patents which will be universal so that it may be used in both on-the-last and off-the-last work, and to provide novel shoe supporting and holding means to enable the heel-seat forming operation to be effectively and expeditiously carried out upon shoes which have had their lasts removed. Accordingly, with these objects in view, the illustrated machine, which is of the type above referred to, is provided with a jack which is constructed and arranged to be used with a plurality of heel plates of different sizes interchangeably, one being selected, and mounted upon the jack, which approximately fits the heel-seat portion of the interior of a given shoe thereby providing for firmly supporting the shoe during the heel-seat forming operation and at the same time holding it from lateral movement relatively to the jack. In order to prevent rearward movement of the shoe relatively to the plate during the heel-seat forming operation, the illustrated machine is provided with a member mounted upon the jack at the rear of the plate on the jack for movement toward and away from the plate and arranged to engage the rear end of the shoe to clamp it against the plate. Also, as illustrated, the clamping member is constructed and arranged to be swung laterally of the plate out of the way of the shoe positioned upon the plate so that the operator may, without interference of the clamping member and while the heel-seat portion of the shoe is under pressure, employ a hammer to pound up and shape the shoe around the heel-seat portion thereof. Movement of the clamping member out of the way of the shoe also facilitates the removal of the shoe after the forming operation and the placing of another shoe upon the jack. In the illus-

trated machine the clamping member is normally urged toward the supporting plate by a spring, and a stop is provided for limiting the movement of the clamping member toward the plate.

On the other hand, when it is desired to use the illustrated machine for operating on shoes on the last, it is only necessary to remove a block carrying the plate and to substitute therefor a block carrying a last pin.

With the above and other objects and features in view, the invention will now be described with reference to the accompanying drawing and pointed out in the claims.

Referring to the drawing:

Fig. 1 shows the top portion of a heel-seat forming machine illustrating a jack having a shoe supporting plate and a die which cooperate with one another to form or mold a heel-seat portion of a shoe positioned upon the plate, together with a member for cooperating with the plate to clamp the shoe in position upon the plate during the heel-seat forming operation;

Fig. 2 is a side view of the top portion of the jack and its shoe supporting plate, the plate having a shoe positioned thereon and the jack being provided with the member which cooperates with the plate to clamp the shoe to the plate; and

Fig. 3 is a perspective view of the jack shown in Fig. 2 illustrating the member thrown out of the clamping position shown in Fig. 2 and rocked to the right relatively to the jack, the upper portion of the jack being taken apart clearly to show the construction of shoe supporting parts of the jack.

As above stated, the illustrated machine is of the type disclosed in the above-identified Letters Patent which may be consulted for a better understanding of such features that are not hereinafter described. The illustrated machine, like those set forth in the Letters Patent referred to, comprises a shoe supporting jack 10 pivoted to a shaft 12 (Fig. 1) which is mounted for reciprocation in the frame 14 of the machine toward and away from a die 16 of the desired shape secured to the frame 14 in any convenient manner. The jack 10 comprises a post 18 having an upper bifurcated portion 20 arranged to receive a tongue portion 22 of a carrier 24, the lower surface 26 (Fig. 2) of the tongue portion 22 being curved and serrated to engage a curved, serrated surface 28 of the post 18 so that the carrier 24 may be canted at a desired angle to the post 18 for properly reacting against the molding pressure of the die 16. The tongue portion 22 of the carrier 24 is also provided with a slot 30 through which extends a screw 32 carried by the post for clamping the carrier 24 in adjusted position to the post 18, the slot 30 being wider than the screw 32 which passes through it so that

the carrier 24 may be slightly raised away from the serrated surface 28 of the post 18 for setting the carrier at different positions upon the post 18.

When it is desired to operate upon shoes off the last, a block 34 is substituted for the corresponding block disclosed in the above-mentioned Letters Patent. The block 34 is supported upon the carrier 24 and is provided with a dove-tail flange 36 arranged to slide in a correspondingly shaped recess 38 in the top surface of the carrier 24 to permit an amount of rectilinear sliding movement of the block 34 relatively to the carrier 24 transversely of the shoe to be supported. This sliding movement is limited by a stud 40 (Fig. 3) slideable in a recess 42 in the carrier 24, the stud being arranged to enter an elongated recess 43 in the bottom surface of the block 34. The stud 40 is normally forced upwardly into the elongated recess 43 by a spring 44 and may be drawn out of the recess 43 by depressing a screw 46 attached to the stud 40 so as to permit removal of the block 34 from the jack.

In order effectively to support the heel-seat portion of a shoe off the last during the heel-seat forming operation, the block 34 is provided with a flat upper surface 48 (Fig. 3) constructed and arranged to receive a series of supporting plates 50 of different sizes and shapes which serve as supports for the heel-seat portions of shoes mounted upon the jack, each of the plates 50 being similar in shape to the heel-seat portion of the last upon which a shoe is made. Each of the plates 50 is rigidly held in correct position upon the block 34 by a stud 52 of considerable length which fits into a recess 54 in the upper surface 48 of the block 34 and by a short pin 56 depending from each of the plates and arranged to fit into a recess 58 in the upper surface 48 of the block 34 to assist in positioning the plate upon the block and prevent rotation of the plate about its stud 52.

Each of the plates 50 is locked upon the block 34 by a catch 60 which engages a notch 62 in the stud 52. When it is desired to remove the plate 50 from the block 34, the catch 60 is released by manually pushing a rod 64 connected to the catch and extending beyond a side of the block against pressure of a spring 65 carried by the rod 64.

In order to cooperate with the plate 50 for clamping the shoe in position thereon as shown in Fig. 2 so that the operator will not be required to hold the shoe against displacement relatively to the plate as the jack 10 is moved toward the die 16, there is provided a finger 66 mounted for movement toward and away from the plate 50.

The mechanism for supporting the finger 66 and for controlling the operation thereof will next be described. Attached to the rear surface of the carrier 24 by screws 68 is an

5 arm 70 having a downwardly extending portion 72 provided with a cylindrical recess 74 arranged to receive a stud 76 (Fig. 2) secured to a finger supporting member 78 about which stud the finger 66 may be rocked for purposes later to be described.

In order that the finger 66 may be supported for movement toward and away from the plate 50 for engaging the rear portion of a shoe mounted upon the plate, the finger-supporting member 78 is provided with a pin 80 extending therethrough, upon the end portions of which pin projecting legs 82 of the finger 66 are mounted to straddle opposite sides of the finger-supporting member 78. 10 The lower portions of the finger 66 and the finger-supporting member 78 are provided with hand grips 84, 86 respectively, supporting between them a spring 88 which tends to rotate the finger 66 in a counterclockwise direction (Fig. 2) about the pin 80 thus normally urging the shoe-engaging portion 90 of the finger 66 downwardly and to the left against the rear portion of the shoe near its sole when the finger-supporting portion 78 is in its vertical position as shown in Fig. 2. 15

20 When it is desirable to move the finger 66 away from the shoe during the period in which the shoe is under pressure in order that the operator may hammer the rear portion of the shoe to shape properly the portions of the shoe surrounding the heel-seat portion of the sole, or where the block 34 has been removed and a block such as shown in the 25 above referred to Letters Patent is to be substituted therefor to equip the machine to operate upon shoes on the last, the finger 66 together with the finger-supporting member 78 is swung or rocked about the stud 76 to a 30 position shown in Fig. 3.

In order correctly to locate and set the finger 66 in upright position (Figs. 1 and 2) for clamping the shoe and to permit it to be swung conveniently laterally of the jack as 35 above described, the upper end of the depending portion 72 of the arm 70 is provided with a pair of slideways 92 (Fig. 3) and a socket 94 which cooperates with a spring-pressed ball plunger 96 (Fig. 2) mounted in 40 a cylindrical recess 98 of the finger-supporting member 78, the plunger 96 being released by positively swinging the finger-supporting member 78 together with the finger 66 laterally of the jack about the stud 76. The 45 lateral displacement of the finger 66 about the stud 76 at opposite sides of the jack is limited by shoulders 100 (Fig. 2) located upon opposite sides of the depending portion 72 of the arm 70, one of which shoulders engages a protruding lug 102 of the finger-supporting member 78 as the finger is displaced from its upright operative position. 50

The minimum distance between the finger 66 and the shoe supporting plate 50 may conveniently be regulated by a screw 104, the

inner end 106 of which is arranged to engage the upper portion of a face 108 of the finger-supporting member 78, which screw extends through the finger 66 and is clamped in adjusted position relatively to the finger 66 by 50 a check nut 110.

In carrying out the heel-seat forming operation, the operator presses the hand grips 84, 86 together so as to space the shoe-engaging portion 90 of the finger 66 as far as possible from the plate 50. The shoe is then placed upon the plate 50 in an inverted position (Fig. 2) and the operator releases his hold of the hand grips, the finger 66 coming into contact with the rear end of the shoe to force it against the adjacent portions of the plate for positioning the shoe upon the plate 50 longitudinally relatively to the die without risk of contact of the finger with the die as the shoe is pressed between the jack and 85 the die.

It will be noted that since the arm 70 is attached to the carrier 24 that the hand grips 84, 86 may be used to effect angular adjustment of the carrier 24 relatively to the post 90 18. Should it be found desirable to operate upon a shoe upon a last, it is only necessary to remove the block 34 and to substitute a block carrying a last pin such as described in the above-mentioned Letters Patent, the finger 66 being swung laterally to a position such as indicated in Fig. 3 so that it will not interfere with the operation of the machine equipped for on-the-last work. 95

Having thus described my invention, what I claim as new and desire to secure by Letters Patent of the United States is:

1. A heel-seat forming machine having, in combination, a heel-seat forming die and a jack mounted for relative movement to form the heel-seat portion of a shoe for the reception of a wood heel, said jack comprising a plate constructed and arranged to support a limited area on the inside of the shoe corresponding to the area to which pressure is applied by the die, said plate corresponding in width substantially to the lateral width of the inside of the shoe to prevent lateral movement of the shoe relatively to the jack, and a member mounted for movement with the jack and for movement toward and away from the rear end of the plate and constructed and arranged to engage the shoe to clamp it against the plate and prevent rearward movement of the shoe relatively to the jack. 105

2. A heel-seat forming machine having, in combination, a heel-seat forming die and a jack mounted for relative movement to form the heel-seat portion of a shoe for the reception of a wood heel, said jack comprising a plate constructed and arranged to support a limited area on the inside of the shoe corresponding to the area to which pressure is applied by the die, said plate corresponding in width substantially to the lateral width 115 120 125 130

of the inside of the shoe to prevent lateral movement of the shoe relatively to the jack, and a lever pivotally mounted for swinging movement toward and away from the rear 5 end of the plate and arranged to engage a shoe at a point substantially in the plane of the plate to clamp the shoe against the plate and prevent rearward movement of the shoe relatively to the plate while the die and jack 10 are being relatively moved to form the heel-seat.

3. A heel-seat forming machine having, in combination, a heel-seat forming die and a jack mounted for relative movement to form the heel-seat portion of a shoe for the reception of a wood heel, said jack comprising a plate constructed and arranged to support a limited area on the inside of the shoe corresponding to the area to which pressure is 15 applied by the die, said plate corresponding in width substantially to the lateral width of the inside of the shoe to prevent lateral movement of the shoe relatively to the jack, a lever pivotally mounted upon the jack for swinging movement toward and away from the rear end of the plate, and means for normally swinging the lever toward the plate to clamp the shoe against the plate.

4. A heel-seat forming machine having, in combination, a heel-seat forming die and a jack mounted for relative movement to form the heel-seat portion of a shoe for the reception of a wood heel, said jack comprising a plate constructed and arranged to support a limited area on the inside of the shoe corresponding to the area to which pressure is applied by the die, a member mounted on the jack and having a projecting handle portion, a lever pivotally mounted on said member for swinging movement toward and from the rear end of the plate, and a spring for forcing the lever toward the plate to engage the shoe and clamp it against the plate, said lever having a handle extending beyond its 40 pivot in coöperative relation to said handle portion, said handle and handle portion being relatively operable to release the clamping pressure on the shoe.

5. A heel-seat forming machine having, in combination, a heel-seat forming die and a jack mounted for relative movement to form the heel-seat portion of a shoe for the reception of a wood heel, said jack comprising a plate constructed and arranged to support a limited area inside of the shoe corresponding to the area to which pressure is applied by the die, said plate corresponding in width substantially to the lateral width of the inside of the shoe to prevent lateral 55 movement of the shoe relatively to the jack, a member mounted upon the jack for movement toward and away from the rear end of the plate to engage the rear end of the shoe, and means normally urging the member toward the shoe to clamp the shoe against 60

the plate and prevent rearward movement of the shoe relatively to the jack.

6. A heel-seat forming machine having, in combination, a die, a jack mounted for movement relatively to the die to form a heel-seat portion of a shoe upon the jack, said jack comprising a plate constructed and arranged to support the shoe by engagement with a limited area of the inside of the shoe for facilitating the mounting of the shoe upon the jack and the removal of the shoe therefrom, and a member constructed and arranged for movement to engage and disengage the rear portion of the shoe for clamping it against the plate, said member also being mounted for movement at an angle to the direction of said movement to position it out of contact with the shoe and in an inoperative position.

7. A heel-seat forming machine having, in combination, a die and a jack mounted for relative movement to form a heel-seat portion of a shoe positioned upon the jack, said jack being constructed and arranged to receive either a plate or a last pin carrying member to adapt the machine for off-the-last or on-the-last work respectively, and a member constructed and arranged to engage the rear portion of the shoe to clamp it against the plate when the machine is operating on off-the-last work, said member also being constructed and arranged to be swung out of contact with the shoe on the plate and into inoperative position when the machine is operating upon on-the-last work.

8. A heel-seat forming machine having, in combination, a die, a jack mounted for movement relatively to the die to form a heel-seat portion of a shoe upon the jack, said jack comprising a plate constructed and arranged to support the shoe by engagement with a limited area of the inside of the shoe for facilitating the mounting of the shoe upon the jack and the removal of the shoe therefrom and to position the shoe upon the jack, and a spring-pressed member constructed and arranged yieldingly to engage the rear portion of the shoe for clamping it against the plate during a portion of the heel-seat forming operation, said member also being mounted for movement at an angle to the direction of said yielding movement for positioning it out of contact with the shoe upon the plate during another portion of said operation.

9. A heel-seat forming machine having, in combination, a die, a jack mounted for movement relatively to the die to form a heel-seat portion of a shoe upon the jack, said jack comprising a plate constructed and arranged to support the shoe by engagement with a limited area of the inside of the shoe for facilitating the mounting of the shoe upon the jack and the removal of the shoe therefrom and to position the shoe upon the

5 jack, a member mounted for movement toward and away from the plate and arranged to engage the shoe positioned on the plate for clamping it against the same, and an adjustable stop between the member and the jack to limit the movement of the member toward the plate.

10. A heel-seat forming machine having, in combination, a die, a jack mounted for movement relatively to the die to form a heel-seat portion of a shoe upon the jack, said jack comprising a plate constructed and arranged to support the shoe by engagement with a limited area of the inside of the shoe for facilitating the mounting of the shoe upon the jack and the removal of the shoe therefrom and to position the shoe upon the jack, a member mounted upon the jack and arranged for movement toward and away from the plate for engaging the rear portion of the shoe to clamp it against the plate, and a spring normally to urge the member toward the plate.

15. A heel-seat forming machine having, in combination, a die, a jack mounted for movement relatively to the die to form a heel-seat portion of a shoe upon the jack, said jack including a plate constructed and arranged to support the shoe by engagement with a limited area of the inside of the shoe for facilitating the mounting of the shoe upon the jack and the removal of the shoe therefrom and to position the shoe upon the jack, a member mounted upon the jack and arranged for movement toward and away from the plate for engaging the rear portion of the shoe to clamp it against the plate, and adjustable means to vary the extent of movement of the member toward the plate.

20. 12. A heel-seat forming machine having, in combination, a die and a jack mounted for relative movement to form a heel-seat portion of a shoe positioned upon the jack, said jack including a plate constructed and arranged to serve as a support for the shoe against the forming pressure of the die, and a member mounted for movement toward and away from the plate substantially longitudinally of the jack and arranged for engaging the rear portion of the shoe positioned upon the plate to clamp it against the plate, said member also being mounted for movement laterally of the jack to swing the member away from the plate.

25. 13. A heel-seat forming machine having, in combination, a die and a jack mounted for relative movement to form a heel-seat portion of a shoe positioned upon the jack, said jack including a plate constructed and arranged to serve as a support for the shoe against the forming pressure of the die, and a member mounted upon the jack and arranged for pivotal movement substantially longitudinally of the jack toward and away from the plate for engaging the rear por-

tion of the shoe to clamp it against the plate, said member also being mounted for movement substantially transversely of the jack to move the member away from the plate.

30. 14. A heel-seat forming machine having, in combination, a heel-seat forming die and a jack mounted for relative movement to form the heel-seat portion of a shoe for the reception of a wood heel and constructed and arranged to render the counter portion of the shoe, the heel seat portion of which is being subjected to pressure to form the heel seat, readily accessible for a pounding operation, said jack comprising a detachable plate constructed and arranged to support a limited area inside of the shoe corresponding to the area to which pressure is applied by the die, said plate corresponding in width substantially to the lateral width of the inside of the shoe to prevent lateral movement of the shoe relatively to the jack, the limited longitudinal extent of said plate facilitating the mounting of the shoe on the jack and its removal therefrom.

35. 15. A heel-seat forming machine having, in combination, a die and a jack mounted for relative movement to form a heel-seat portion of the sole upon the jack, said jack comprising a plate similar to the heel portion of the inside of a shoe constructed and arranged to support the shoe by engagement with only the rear portion of the inside of the shoe for facilitating the mounting of the shoe upon the jack and the removal of the shoe therefrom and to position the shoe relatively to the jack, a member movable with the jack and also mounted for movement toward and away from the rear end of the plate and arranged for engaging the shoe to clamp it against the plate to prevent lengthwise movement of the shoe relatively to the jack, and a spring arranged to urge the member toward the plate.

40. 16. A heel-seat forming machine having, in combination, a die, a jack mounted for movement relatively to the die to form a heel-seat portion of the shoe upon the jack, said jack comprising a plate constructed and arranged to support the shoe by engagement with only the rear portion of the inside of the shoe for facilitating the mounting of the shoe upon the jack and the removal of the shoe therefrom, and a member mounted upon the jack and arranged for movement toward and away from the plate for engaging the rear portion of the shoe to clamp it against the plate, said member also being mounted for movement laterally of the shoe for positioning it in inoperative position.

45. 17. A heel-seat forming machine having, in combination, a die and a jack mounted for relative movement to form a heel-seat portion of a shoe upon the jack, said jack comprising a thin plate of substantially the same size and shape as the heel portion of the insole of the shoe being operated upon con-

- structed and arranged to support the shoe by engagement with a limited area of the inside of the shoe for facilitating the mounting of the shoe upon the jack and the removal of the shoe therefrom and also to position the shoe upon the jack, said plate having a notched pin to enter the jack and a spring latch to engage the notch in the pin to hold the plate in place.
18. A heel-seat forming machine having, in combination, a die and a jack mounted for relative movement to form a heel-seat portion of a shoe positioned upon the jack, said jack being adapted to receive interchangeably one of a plurality of plates for fitting the heel portions of insoles of shoes of different sizes and shapes, each of the plates being constructed and arranged substantially to fit the heel portion of the inside of the shoe and to support the shoe by engagement with only the rear portion of the inside of the shoe for facilitating the mounting of the shoe upon the jack and the removal of the shoe therefrom and each of said plates having a plurality of pins for entering holes in the jack, the jack having pressure released means engaging one of the pins for retaining the plate upon the jack.
19. A heel-seat forming machine having, in combination, a die and a jack mounted for relative movement to form a heel-seat portion of a shoe off the last and positioned upon the jack, said jack being constructed and arranged to receive either a plate or a last-pin-carrying member to adapt the machine for off-the-last or on-the-last work, respectively, and a member mounted for movement lengthwise of the shoe for engaging the rear portion of the shoe to clamp it against the plate when the machine is operating on off-the-last work, said member also being mounted for movement laterally of the shoe for swinging the member away from the shoe and into inoperative position when the machine is operating on on-the-last work.
20. A heel-seat forming machine having, in combination, a die and a jack mounted for relative movement to form a heel-seat portion of a shoe off the last and positioned upon the jack, said jack being adapted to receive interchangeably one of a plurality of plates, each of the plates being constructed and arranged to serve as a support for the shoe against the pressure of the die and to prevent lateral movement of the shoe relatively to the jack, and a member mounted for movement with the jack and also mounted for movement toward and away from the jack for engaging the rear portion of the shoe and also mounted for movement laterally of the shoe to move the member into inoperative position during a portion of the heel-seat forming operation.
21. A heel-seat forming machine having, in combination, a die, a jack mounted for movement relatively to the die for forming the heel-seat portion of a shoe positioned upon the jack, said jack being adapted to receive interchangeably one of a plurality of plates each of which is constructed and arranged to support the shoe against the pressure of the die and prevent lateral movement of the shoe relatively to the jack and also being constructed and arranged to receive a last-pin-carrying member to adapt the machine for on-the-last work, and a clamp member mounted for movement for engaging the shoe to hold it against the plate when the machine is operating on off-the-last work, said member also being mounted for movement laterally of the shoe upon the jack to swing the member into inoperative position when the machine is operating upon on-the-last work.
22. A heel-seat forming machine having, in combination, a die for forming the heel-seat of a shoe for the reception of the cup of a wood heel and a jack mounted for relative movement to form the heel-seat of the shoe positioned upon the jack, said die and said jack being constructed and arranged to render the counter portion of the shoe, the heel seat portion of which is being subjected to pressure to form the heel seat, readily accessible for a pounding operation, said jack comprising a block constructed and arranged to be positioned upon the jack and to be removed therefrom, and a plate carried by the block and constructed and arranged to correspond to the peripheral dimensions of the heel portion of the inside of the shoe, said block being constructed and arranged to receive interchangeably plates of different sizes and shapes.
23. A heel-seat forming machine having, in combination, a heel-seat forming die and a jack mounted for relative movement to form a heel-seat of a shoe positioned upon the jack, said jack comprising a block constructed and arranged to be positioned upon the jack and to be removed therefrom, a plate carried by the block and constructed and arranged to engage the heel portion of the inside of the shoe, and a member carried by the jack and constructed and arranged to engage the rear end of the shoe for retaining the shoe in position upon said plate.
24. A heel-seat forming machine having, in combination, a heel-seat forming die and a jack mounted for relative movement to form a heel portion of a shoe positioned upon the jack, said jack being constructed and arranged to receive either a plate or a last-pin-carrying member to adapt the machine for off-the-last or on-the-last work, respectively, and a member constructed and arranged to engage the rear portion of the shoe to clamp it against the plate when the machine is operating on off-the-last work, said member being constructed and arranged for movement widthwise of the shoe out of contact

with the rear portion of the shoe and into inoperative position.

25. A heel-seat forming machine having, in combination, a heel-seat forming die and a jack mounted for relative movement to form the heel-seat portion of a shoe for the reception of a wood heel, said jack comprising a plate constructed and arranged to support a limited area inside of the shoe corresponding to the area to which pressure is applied by the die, said plate corresponding in width substantially to the lateral width of the inside of the shoe to prevent lateral movement of the shoe relatively to the jack, a member pivotally mounted on the jack for movement about an axis extending lengthwise of the plate, and a lever pivoted to the member for swinging movement toward and away from the rear end of the plate to clamp the rear end of the shoe against the plate and prevent rearward movement of the shoe relatively to the plate while the die and jack are being relatively moved to form the heel-seat, the member and lever being movable about the axis of the member to dispose the lever in an inoperative position.

In testimony whereof I have signed my name to this specification.

EARL A. BESSOM.
